Primary Examiner — Lauren R Calve(74) *Attorney, Agent, or Firm* — Jose Cherson Weissbrot(57) **CLAIM**

The ornamental design for a retractable hanger, as shown and described.

DESCRIPTION

FIG. 1 is a first perspective view of a retractable hanger showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the retractable hanger thereof; and,

FIG. 10 is a partial enlarged view of the selected portion 10 in FIG. 1.

The broken lines shown in the drawings depict portions of the retractable hanger that form no part of the claimed design.
